UNITED STATES PATENT OFFICE.

CHARLES A. BABCOCK, OF BUFFALO, NEW YORK.

FLUTING-MACHINE.

SPECIFICATION forming part of Letters Patent No. 224,323, dated February 10, 1880.

Application filed June 18, 1878.

To all whom it may concern:

Be it known that I, CHARLES A. BABCOCK, of the city of Buffalo, in the county of Erie and State of New York, have invented certain new and useful Improvements in Fluting-Machines, of which the following is a specification, reference being had to the accompanying drawings.

My invention relates to a fluting-machine in which a corrugated or fluted bed is used in connection with a corrugated or fluted roller which is operated by hand. In this class of fluters it is of importance that the handle of the roller should be so arranged as to enable the operator to exert the requisite pressure with as little exertion as possible.

The object of my invention is to construct the handle in such manner as to accomplish this result; and it consists in combining with the fluting-roller a U-shaped shank having openings in the ends of its legs in which turn the journals of the rollers, and having the handle arranged obliquely at the apex of the U-shaped shank, as will be hereinafter more fully set forth.

In the accompanying drawings, Figure 1 is a sectional elevation of a fluting-machine provided with my improvements. Fig. 2 is a top-plan view of the fluting-roller.

Like letters of reference refer to like parts in both of the figures.

A represents the base, provided with a recess in its upper side for the reception of the heater B, and C is the corrugated bed-plate, resting on the heater, and having marginal flanges which overlap the base. D is the cylindrical roller, provided on its circumference with teeth or corrugations in the usual form, and having journals e formed at its ends. E

is the handle-shank, composed of two curved bars or arms joining each other at an acute angle and straddling the journals of the roller. F is the handle, secured to the shank E at the apex or the junction of the two arms constituting the shank, and arranged at an acute angle with reference to a line drawn from the apex of the shank to the center of the fluting-roller, or so as to incline toward the roller. The arms of the shank are, toward their point of junction, curved upward, as clearly shown, so that the upper surface of the shank, at the point where the handle is secured thereto, is at right angles to the axis of the handle.

This peculiar construction of the shank and handle provides sufficient space between the handle and roller for the accommodation of the hand of the operator, and at the same time brings the handle so close to the roller as to render the device very compact. It also enables the operator to move the roller back and forth over the corrugated bed with ease, and places the hand and wrist in the position in which they are least liable to become fatigued.

I claim as my invention and desire to secure by Letters Patent—

The combination, with the fluting-roller D, of the U-shaped shank E and the handle F, secured to the shank E at its apex and inclining toward the roller, substantially as set forth.

In testimony that I claim the foregoing as my invention I have hereto set my hand and affixed my seal in the presence of two subscribing witnesses.

CHAS. A. BABCOCK. [L. S.]
